UNITED STATES PATENT OFFICE.

ALEXANDER F. MACDONALD, OF SCHENECTADY, NEW YORK, ASSIGNOR TO GENERAL ELECTRIC COMPANY, A CORPORATION OF NEW YORK.

COVER FOR TURBINE-BUCKETS.

No. 901,459.

Specification of Letters Patent.

Patented Oct. 20, 1908.

Application filed March 28, 1907. Serial No. 365,023.

To all whom it may concern:

Be it known that I, ALEXANDER F. MACDONALD, a citizen of the United States, residing at Schenectady, county of Schenectady, 5 State of New York, have invented certain new and useful Improvements in Covers or Baffle-Strips for Turbine-Buckets, of which the following is a specification.

The present invention relates to the cover 10 or baffle-strip for the ends of buckets of elastic fluid turbines, and has for its object to improve their construction.

In carrying out my invention, the buckets are mounted upon a suitable support and 15 may be individually secured thereto, formed integrally therewith, cast into the support or secured by any suitable means. The buckets may extend radially with respect to the wheel shaft or in planes parallel therewith. The 20 cover for the free ends of the buckets is composed of a thin strip or ribbon of metal which is sufficiently flexible so that it can be wound around the bucket ends in layers or turns, one over the other, until the desired thickness is 25 obtained. This ribbon is supported by the ends of the buckets and forms one of the walls of the bucket spaces. By using a long strip and winding it round and round the wheel, I avoid all joints in the covering and the 30 labor incident thereto. By making it flexible it is unnecessary to use bending dies as a part of the manufacture. This results in greatly decreasing the cost of the construction and at the same time, simplifies the wheel. The 35 ribbon is made thin so as to be very flexible and readily applied to the bucket ends. Before the ribbon is applied to the buckets it is suitably perforated by means of a punch, which perforations when the ribbon is mounted 40 on the wheel, are adapted to register and receive the bucket securing means. Ordinarily, the perforations will be equally spaced, and in any event should be of sufficient size to permit of the ribbon being slipped over 45 the tenons or other securing means, and enable one turn to lie in contact with the other. The perforations may be made of any suitable shape. For example, they may have straight sides and curved ends, corresponding 50 to the curved surfaces of the buckets, or they may be made round or rectangular, depending upon the character of the means employed to secure the successive layers to the

bucket wheel or drum. By making the ribbon thin, these perforations can easily be 55 made by an ordinary index punch and die, and being thin, can readily be made without danger of burring the stock when the punch passes through the strip. I may use steel or phosphor-bronze for this purpose, or any 60 other material which is capable of withstanding the centrifugal strains to which it will be subjected in practice. The outer end of the ribbon may be secured in place by one of the same tenons or other securing means employed to hold the cover in place, or a special 65 means for the purpose may be provided.

When the free ends of the buckets are parallel with the axis of the wheel, the ribbon will be made perfectly straight, and of 70 a width sufficient to cover the bucket ends and project slightly beyond the sharpened edges on one or both sides, the object of the latter being to protect said sharpened edges. When the free ends of the buckets are made 75 on an incline for the purpose of providing the necessary spaces between the buckets to accommodate the elastic fluid, the sides of the ribbon will be made slightly curved to compensate for the difference in diameter 80 between the inlet and the discharge sides of the bucket. This can readily be done by using a ribbon that is a little thicker on one side than on the other and passing the same through rollers or dies, which decreases the 85 thickness of the ribbon on one side and in so doing, elongates said side and causes the finished product to be curved on an arc of large radius, which radius would vary with the amount of inclination of the bucket ends, 90 the diameter of the wheel, etc.

In the accompanying drawing, which illustrates certain of the embodiments of the invention, Figure 1 is a front elevation of a bucket wheel; Fig. 2 is a section of a wheel 95 showing the covering mounted in place with tenons on the buckets for securing the same in place; Fig. 3 is a partial sectional view in the plane of the wheel; Fig. 4 is a detail view showing a covering applied to wheel 100 buckets having inclined ends; Fig. 5 is a plan view of a metal ribbon provided with perforations through which the cover-securing means extend; Fig. 6 is a plan view of a ribbon before it is perforated and which is 105 adapted to be mounted upon wheel buckets.

of the construction shown in Fig. 4, and Fig. 7 is a detail view of a slight modification of the cover securing means.

1 is a wheel, keyed or otherwise secured to 5 the shaft 2 and provided with radial buckets 3. Surrounding the buckets and wound thereon in layers and forming the outer wall of the bucket spaces, is a metal strip or ribbon 4. This ribbon is provided with per- 10 forations 5. The buckets 3 are provided with integral tenons 6 which extend through the perforations in the ribbon and are riveted over at their outer ends to secure said cover in place. Instead of providing the 15 buckets with tenons, I may employ screws or other means 7 for holding the cover in place, as shown in Fig. 7. In this case, the cover may be applied while unperforated, and said perforations made afterwards. 20 Preferably, the outer end 8 of the ribbon terminates at a point adjacent to one of the tenons or other securing means so as to hold the same in place and prevent it from bending outwardly under the effects of centrifugal force. The inner end 9 may be located 25 at a point between two buckets. When, for any reason, the buckets are widely spaced, I may provide means such as small rivets for holding the ends of the ribbon, which rivets 30 pass through said ends in a radial direction and are riveted over to hold the same in place.

When the turbine is of the radial flow type and the buckets are arranged in concentric circles, the same form of covering may be used except that the ribbon would be wound edgewise in suitable winding machines, and to a diameter corresponding to the diameter of the particular row of buckets to which it is adapted to be attached. As now constructed, these winding machines are capable of winding a small ribbon edgewise and at the same time maintaining the same thickness of stock at all points and 45 avoiding any tendency of the ribbon to buckle.

The invention is applicable to machines operating on the impact or reaction principle, or upon a modification of the impact 50 or reaction principle.

By using a metal ribbon for a cover and applying it in the manner specified, I avoid the losses in stock which would result if made in small pieces. The cover can be applied to the buckets more rapidly than the constructions heretofore proposed, and the saving in the cost of labor is very considerable.

In accordance with the provisions of the 60 patent statutes, I have described the principle of operation of my invention, together with the apparatus which I now consider to represent the best embodiment thereof; but I desire to have it understood that the appa-

ratus shown is only illustrative, and that the invention can be carried out by other means.

What I claim as new and desire to secure by Letters Patent of the United States, is,—

1. An elastic fluid turbine comprising a plurality of buckets and a support therefor, 70 in combination with a ribbon that is wound in layers around the ends of the buckets and forms a cover therefor.

2. An elastic fluid turbine comprising a 75 plurality of buckets and a support therefor, in combination with a metal ribbon that is wound in layers around the ends of the buckets and forms a cover therefor, and means for securing the layers to the buckets.

3. An elastic fluid turbine comprising a 80 plurality of buckets and a support therefor, in combination with a cover for the free ends of the buckets which is wound around the bucket ends in layers one on top of the other, and individual means for securing the cover 85 in place at a plurality of points.

4. An elastic fluid turbine comprising a plurality of buckets and a support therefor, 90 in combination with a cover for the buckets made of thin flexible and perforated material which is wound around the bucket ends, one turn on top of the other with the perforations registering, and securing means therefor which pass through said perforations.

5. An elastic fluid turbine comprising a 95 plurality of buckets and a support therefor, in combination with a cover for the bucket ends made of thin metallic ribbon wound around the bucket ends one turn on top of and resting on the other, the said ribbon 100 being perforated, and tenons formed integral with the buckets which pass through the perforations, and are riveted over at their ends to secure the cover in place.

6. An elastic fluid turbine comprising a 105 plurality of buckets and a support therefor, in combination with a cover forming a wall of the bucket spaces made of a long, thin ribbon and wound a number of times around the ends of the buckets, and means located at 110 each bucket for attaching the turns.

7. An elastic fluid turbine comprising a plurality of buckets and a support therefor, 115 in combination with a cover forming a wall of the bucket spaces which is made of a thin, metal ribbon wound around the bucket ends to form successive layers, the sides of said ribbon being curved to compensate for the inclination of the bucket ends.

8. An elastic fluid turbine comprising a 120 plurality of buckets and a support therefor, in combination with a cover forming a wall of the bucket spaces which is made up of a thin metallic ribbon wound around the bucket ends to form layers, and a means to 125 secure the outer end of the ribbon and prevent it from being displaced by centrifugal force.

9. An elastic fluid turbine comprising a plurality of buckets and a support therefor, in combination with a covering for the bucket ends that also forms a wall of the bucket spaces, the said covering being wound more than once around the buckets and their support.

In witness whereof, I have hereunto set my hand this 26th day of March, 1907.

ALEXANDER F. MACDONALD.
